UNITED STATES PATENT OFFICE.

SAMUEL D. GEORGE, OF BROOKLYN, ASSIGNOR TO THE AMERICAN LITHOGRAPHIC COMPANY, OF NEW YORK, N. Y.

DESIGN FOR A PATTERN FOR CIGAR-BOXES.

SPECIFICATION forming part of Design No. 24,030, dated February 12, 1895.

Application filed January 14, 1895. Serial No. 534,921. Term of patent 7 years.

To all whom it may concern:

Be it known that I, SAMUEL D. GEORGE, a citizen of the United States, residing at Brooklyn, in the county of Kings and State of New 5 York, have invented and produced a new and original Design for an Ornamental Pattern for Cigar-Boxes; and I do hereby declare the following to be a full, clear, and exact description of the same, reference being had to the accompanying drawing, forming a part thereof.

The leading feature of my design is a horizontal panel affixed to which is a shield-like device.

10 The design is placed on the cigar box as shown in the drawing and consists of a horizontal panel surrounded by ornamental scroll and ribbon work, while in the center, affixed to the top of the design, is a shield-like device, containing a Maltese cross and surmounted by a crown.

20

I claim—

The design for an ornamental pattern for cigar boxes, substantially as shown and described.

In testimony whereof I affix my signature, 25 in the presence of two witnesses, January 5, 1894.

SAMUEL D. GEORGE.
